DESIGN FOR A BEAM ASSEMBLY FOR A WEIGHING SCALE

Henry Dreyfuss, New York, N. Y., assignor to
Fairbanks, Morse & Co., Chicago, Ill., a corpora-
tion of Illinois

Application June 22, 1944, Serial No. 114,149

Term of patent 14 years

(Cl. D52—10)

To all whom it may concern:

Be it known that I, Henry Dreyfuss, a citizen
of the United States, residing at New York city,
in the county of New York and State of New York,
have invented a new, original, and ornamental
Design for a Beam Assembly for a Weighing
Scale, of which the following is a specification,
reference being had to the accompanying draw-
ing, forming part thereof.

In the drawing, the figure is a perspective view
of a beam assembly for a weighing scale, showing
my new design.

I claim:

The ornamental design for a beam assembly
for a weighing scale, as shown.

HENRY DREYFUSS.
